Primary Examiner — Stacia A Cadmus(74) *Attorney, Agent, or Firm* — Global IP Counselors, LLP(57) **CLAIM**

The ornamental design for a wheel for an automobile, as shown and described.

DESCRIPTION

FIG. 1 is a front elevational view of a wheel for an automobile in accordance with my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and, FIG. 7 is a front side perspective view thereof.

The inside surfaces of the wheel, shown in broken lines in FIGS. 2 and 7, form no part of the claimed design since the inside surfaces are hidden when the wheel is mounted to the automobile.

A second embodiment of my new design includes the mirror image of the wheel shown in FIGS. 1 to 7.
